UNITED STATES PATENT OFFICE.

L. EUGENE FULLER AND JOSEPH H. MACAULEY, OF CHICAGO, ILLINOIS.

COOLING APPARATUS FOR PAINT-MILLS.

SPECIFICATION forming part of Letters Patent No. 295,626, dated March 25, 1884.

Application filed October 8, 1883. (No model.)

To all whom it may concern:

Be it known that we, L. EUGENE FULLER and JOSEPH H. MACAULEY, citizens of the United States, residing at Chicago, in the county of Cook and State of Illinois, have invented certain new and useful Improvements in Cooling Apparatus for Paint-Mills, of which the following is a specification, to wit:

This invention relates to an improvement in cooling apparatus for paint-mills; and it consists in the peculiar construction and arrangement of the same, whereby the water for cooling the upper stone is passed directly to the lower stone and cools it before being carried off by the waste-pipe, while at the same time the proper adjustment of the stones with reference to each other is not impeded, substantially as will be hereinafter more fully described, and pointed out in the claims.

20 In order to enable others skilled in the art to which our invention appertains to make and use the same, we will now proceed to describe its construction and operation, referring to the accompanying drawings, in which—

25 Figure 1 is a central vertical section of the two stones and their cases and the main connecting portions of a paint-mill. Fig. 2 is a plan view of the upper case; Fig. 3, a similar view of the lower case with the stone removed. 30 Fig. 4 is a vertical section of the pipes connecting the upper and lower cases. Fig. 5 represents the coupling at the lower end of these pipes; and Fig. 6 is a side elevation of a paint-mill, showing the relative positions of different parts of our invention.

35 A represents the main frame of a paint-mill, provided with the usual mixer, A', and a driving-shaft, A'', giving motion in the usual way by suitable gearing, both to the mixer and to the lower stone of the mill.

Upon the main frame, in a suitable position with reference to the other parts, is supported the case B, of cylindrical form, in which is secured the upper or stationary stone, B', which 45 does not quite fill the case, but a small space is left between the top and sides of the stone and case, as seen at b, Fig. 1, to allow of the circulation of water around the stone, the latter being secured in the case by a suitable 50 packing, b', which makes a water-tight joint and prevents any leakage.

Below the upper stationary stone, B', is arranged the running-stone C, also set in a case, C', which incloses the stone, both inside and out, with a space, c, for the circulation of water, as already described. The center of the case C' forms a covered chamber, C'', which rises through the center of the stone C, as fully represented in Fig. 1.

55 Formed with or attached to the bottom of the case C' is the supporting-spindle D, having its upper end formed hollow for a short distance, and opening into the water-chamber C'' through a pipe, D', extending up through this chamber, and having its upper end perforated, as seen at d. The hollow spindle is also provided with a series of horizontal tubes, d', passing through the water-chamber and opening into the space c under the stone C.

60 Below the case C' in the main frame of the mill is arranged a plate, E, through which the spindle D passes, which plate is formed with a cored passage, e, the outer end of which may be connected in any suitable manner with a waste-pipe for carrying off the water, and its 65 inner end terminates in a circular chamber, e', which is in communication with the hollow spindle D by means of a hole, d', in its side. The upper or stationary case, B, is provided with a partition, b'', which closely fits the 70 inner end of the stone, and cuts in two the circulating-space, b, as shown in dotted lines in Fig. 2. The supply-pipe F is connected with the case B on one side of this partition, and on the other side is connected a waste-pipe, F', which 75 is by a short section, F'', connected to the diametric center of the water-chamber C'' of the lower or running case, C'.

80 To allow of the vertical adjustment of the lower stone and its case, it is necessary to make 85 a sliding connection between the pipes F' F'', and we accomplish this in the following manner, as clearly represented in Fig. 4: The upper end of the short section F'' is formed with a flange, f, and is free to move in a cylindrical chamber, f', in the union or coupling F''. This coupling is attached to the end of the pipe F' by a screw-plug, f'', and to its lower end is secured a stuffing-box, f'', surrounding the section F'', and is formed with an extension, f'', which 90 extends downward around the short pipe-section a short distance, and protects it

from contact with the paint or varnish, which might prevent its free movement in the coupling. The lower end of the section F^2 is provided with a socket, G , formed with interior 5 inclined sockets, $g\ g$, and the top of the water-chamber C^2 is provided with a nipple, G' , having two wedge-shaped projections, which enter the socket G , and are firmly locked there in when the nipple is turned by being forced 10 up in the sockets $g\ g$, as will be understood by reference to Figs. 4 and 5. The spindle of the running-stone is stepped in a lever, H , having an adjusting-screw, H' , as shown in Fig. 6, by which means this stone is raised or lowered in 15 the ordinary way.

In operation, the water is forced into the upper case under pressure, and, passing entirely around it, is passed into the chamber C^2 through the pipes $F'\ F^2$ and their adjustable 20 coupling. After circulating around the lower stone, C , the water is passed off through the pipes d' , hollow spindle D , and cored plate E . During this operation the chamber C' becomes 25 filled, and the water entering here has time to cool before it is forced around the lower stone and passed off, as described.

While we prefer to use water under pressure, it may also be used without the pressure, and in that case the ends of the tubes d' are 30 plugged up through openings in the side of the case made for that purpose, and the water exhausted from the chamber C^2 through the overflow-pipe in the upper end of the hollow spindle. It will be observed that by this arrangement the water used for cooling the upper stone is passed to the lower one before exhausting, thus saving a great amount, and at 35 the same time the proper relative adjustment of the stones and the removal of the lower

one for repairs, &c., is not interfered with, the 40 sliding union allowing the section F^2 to have a vertical as well as a revolving motion, and the flange preventing its accidental withdrawal through the packing-box.

Having thus fully described our invention, 45 what we claim as new, and desire to secure by Letters Patent, is—

1. In a paint-mill, the running-stone C , casing C' , having a circulating-space around the stone, and the hollow spindle D , in combination 50 with the plate E , through which the spindle passes, formed with the cored passage e and chamber e' , substantially as shown and described.

2. In a paint-mill, the running-stone C and 55 its case C' , formed with a circulating-space around the stone, and with the receptacle C^2 , in combination with the hollow spindle D , pipes d' , and extension D' , formed with perforations d , substantially as and for the purpose 60 set forth.

3. In a paint-mill, the stationary stone B' , its case B , having a circulating-space, b , and the partition b^2 , the supply-pipe F , connected on one side of said partition, and the pipe F' 65 upon the other, the coupling F^3 , and section F^2 , in combination with the coupling G , chamber C^2 , case C' , stone C , and hollow spindle D , all constructed and arranged to operate substantially as and for the purpose set forth. 70

In testimony whereof we have hereunto set our hands in the presence of two witnesses.

L. EUGENE FULLER.
JOSEPH H. MACAULEY.

In presence of—

A. C. JAMES,
FRANK E. REED.
